UNITED STATES PATENT OFFICE.

THEODORE F. TAYLOR, OF BROOKLYN, NEW YORK.

MARKING-STYLUS FOR AUTOMATIC TELEGRAPHS.

SPECIFICATION forming part of Letters Patent No. 293,112, dated February 5, 1884.

Application filed September 18, 1883. (No model.)

To all whom it may concern:

Be it known that I, THEODORE F. TAYLOR, a citizen of the United States, residing in Brooklyn, in the county of Kings and State 5 of New York, have invented certain new and useful Improvements in Marking-Styluses for Automatic Telegraphs, of which the following is a specification.

My invention relates particularly to the 10 class of automatic telegraphs in which the dispatches are prepared for transmission by being transcribed upon the surface of a revolving cylinder by means of spaces left between short sections of non-conducting ink. The 15 ink is applied to the cylinder by means of a pen or stylus, when the latter is in contact therewith. When, however, the stylus is raised from the cylinder, it is essential that the flow of ink should cease. It has been 20 found a matter involving considerable difficulty to properly control the flow of ink.

The object of my invention is to provide a stylus which will apply the ink evenly when in contact with the cylinder, and by means of 25 which its flow may be fully controlled.

The invention consists in narrowing the duct through which the ink is conducted immediately above the nib of the stylus, and in causing it to widen again toward the nib and 30 to terminate in a flattened opening which reaches entirely across the marking-point. By thus narrowing or constricting the ink-duct, I am enabled to prevent a too-rapid flow of the ink, and at the same time avoid the choking 35 which is liable to occur if the duct is narrow throughout its entire length. By again widening the duct into a flattened nib, I am enabled not only to apply the ink in a sufficiently broad line, but I have also found that 40 the ink will flow through the duct more evenly. In the face of the nib I prefer to form a narrow slit or cut extending across the walls of the nib-piece. The effect of this is to cause the ink to flow more freely from the pen as 45 soon as the nib is placed in contact with the surface to which the ink is to be applied. A pen so constructed forms a more regular and even mark.

In the accompanying drawings, Figure 1 is 50 an elevation, partly in section, of a stylus embodying my invention, and Fig. 2 is a detail

drawing, showing the construction of the nib-piece, both views being enlarged.

Referring to the figures, A represents the main portion of the stylus, which is tubular 55 in form; the inner bore *a* serving as a duct for conveying the ink or other non-conducting material from any suitable reservoir to the nib of the stylus. The tube A may be bent 60 into any suitable form for conveniently applying the ink. At the lower end of the section A is attached a nib-piece, B, which consists of a steel or other hard-metal section, about three-quarters of an inch in length, securely fastened to the section A. The nib-piece is preferably secured to the main section 65 by means of a neck, *b'*, entering the section A, and it may be fastened by soldering, brazing, or merely being constructed to fit tightly therein. In some instances it may be found 70 desirable to screw the nib-section into the main section. By thus constructing the nib-section separate from the main section, the former may be replaced, when worn out, without increasing the expense of supplying a new 75 main section, A. Through the nib-piece B is formed a narrow hole, *b*, in diameter about one sixty-second of an inch. This narrow passage constitutes a throttle for the ink-duct, and prevents too rapid flow of ink. The 80 lower end of the nib-piece is flattened, as shown at *c*, and across the end is formed a narrow slit or cut, *d*, such as might be formed by means of a watch-maker's fine saw. The narrow opening *b* is widened into this saw-cut from a distance of about one-eighth of an 85 inch above the slit *d*.

The whole stylus may be supported in any customary manner, a slide-support, *e*, being represented in this instance for this purpose. 90

I claim as my invention—

1. A marking-stylus constructed with an ink-duct narrowed or constricted near its lower extremity, and widened into a flattened opening at the nib, substantially as described. 95

2. A marking-stylus consisting of two sections, the main section and the nib-piece, the latter being constructed with an aperture narrower through a portion of its length than that formed in the main section, and widening 100 at the nib into a flattened opening, substantially as described.

3. A stylus constructed with an ink-duct narrowed through a portion of its length, said stylus terminating in a flattened nib-piece having a slit or cut formed across its face.
- 5 4. The combination, substantially as herein-before set forth, of the main section A, and the nib-piece B, having the narrow aperture *b* and slit *d*.

In testimony whereof I have hereunto subscribed my name this 14th day of September, 1883.

THEODORE F. TAYLOR.
